APPARATUS FOR GRINDING DRILLS AND THE LIKE

Paul H. Needham, Beverly Hills, Calif.

Application November 28, 1947, Serial No. 788,491

8 Claims. (Cl. 51—219)

This invention relates to apparatus for grinding the points of tools and implements, such as twist drills, having generally conical end faces of which the coning angle must be accurately maintained at a determined value and, in addition, a predetermined clearance must be accurately ground from a reference line such as the cutting edge of a twist drill, back to a rear area such as the heel of a twist drill. In the grinding of drills, it is desirable that this clearance angle vary from the cutting edge back to the heel, starting with, e. g. three degrees at the cutting edge and ending with, e. g. fifteen degrees at the heel. It is also necessary that the clearance be the same for each lip of the drill, and that the two cutting edges be exactly symmetrical so that, in rotating, they will describe the same conical surface of revolution. The clearance angle at the cutting edge should be within the range from two to four degrees.

A general object of my invention is to provide a mechanism by the use of which the several lips of a twist drill may be consecutively ground on their end faces with identical coning angle and clearance, and with the clearance varying gradually and uniformly from a predetermined minimum angle at the cutting edge to a predetermined maximum angle at the heel. Such gradual variation of clearance angle produces a clearance, which in cross section is curved gradually from the cutting edge to the heel. This provides for maximum cutting edge strength and durability.

A further object of my invention is to provide an apparatus by the use of which the desired coning angle and clearance can be ground quickly and expeditiously. A further object is to provide an apparatus which may be used by a relatively unskilled operator to grind drill points to exactly the desired shape. To this end, the invention provides an apparatus which will hold and guide a drill so that it is practically impossible for the drill to be improperly ground, the only requirement being that the operator follow a few simple operative steps.

In order to attain a clearance angle starting immediately at the cutting edge, it is necessary to avoid rotating the drill through a complete revolution while in contact with the grinding wheel. Accordingly, a further object of the invention is to provide a grinding apparatus which may be operated so as to present the drill to the grinding wheel with the cutting edge in exactly the proper position for the grinding of the initial clearance angle and the proper coning angle,

to then swing the drill arcuately through a sufficient angle to proceed from the initial clearance angle to the final clearance angle while continuously rotating the drill, shifting the line of contact from the cutting edge to the heel, and maintaining the proper coning angle, and, finally, to withdraw the drill from the grinding wheel and to index the drill so as to bring the other lip of the drill into position for a similar operation.

Another object of the invention is to provide a novel and improved quick acting chuck mechanism for holding the drill.

Other objects will become apparent in the ensuing specifications and appended drawings in which:

Fig. 1 is a front view of a grinding mechanism embodying my invention;

Fig. 2 is a front end view, partially in section, of the chuck and indexing mechanism and associated parts;

Fig. 2a is a sectional view of a modified form of the control linkage;

Fig. 3 is an end view of the apparatus, with the base portions thereof shown in section, as indicated by the line 3—3 of Fig. 1;

Fig. 4 is a diagrammatic end view of the grinding wheel and drill indicating how the arcuate relief angle is produced by the swinging of the drill about the axis of the chuck arbor;

Fig. 4a is an end view of a drill showing the lines of grinding;

Fig. 4b is a side view of the drill indicating the crowning (i. e., relief curvature) of the end surface during grinding;

Fig. 5 is a perspective view of the operating cam assembly of the chuck;

Fig. 6 is a plan view of the apparatus;

Fig. 7 is a horizontal sectional view through the chuck and chuck arbor taken on the line 7—7 of Fig. 8;

Fig. 8 is a transverse sectional view of the chuck;

Fig. 9 is a perspective view of the inner assembly of the chuck;

Fig. 10 is an end view of the assembly shown in Fig. 9; and

Fig. 11 is a perspective view of one of the chuck jaws.

In the machine which is shown herein as an illustrative example of one form in which the invention may be embodied, a grinding wheel 15 is mounted for rotation in a hood 16 which is supported upon a base 17, and is provided with

any conventional driving mechanism for rotating it in the direction indicated by the arrow 18.

The twist drill 19 to be sharpened is mounted in a chuck, indicated generally at 20, in which it is held at an axis which, in plan (Fig. 6) subtends an angle with reference to the plane of the grinding wheel 15 such as to determine the proper coning angle for the cutting edges of the drill. The invention provides means which will be described hereinafter, for adjusting this coning angle within limits.

Viewed from the end of the grinding wheel axis as in Figs. 3 and 4, the drill axis is inclined downwardly and away from the grinding wheel at an angle which, with reference to the horizontal, may be varied from a minimum limit of e. g. three degrees, to a maximum limit of e. g. fifteen degrees. In Fig. 4, at its minimum angle of declination below the horizontal, the drill is shown in full lines and at its maximum angle of declination it is shown in dotted lines. The maximum angle is also shown in Fig. 3. These two positions of the drill determine minimum and maximum angles of relief that are ground on the end face of the drill from the cutting edge, indicated at 21 in Fig. 4 to the heel, indicated at 22 in Fig. 4. Between these minimum and maximum angles of relief, there will be a constantly varying relief angle so that the end face of the drill is continuously curved from the cutting edge to the heel. That is, a cross section taken through a lip of the drill in a plane at right angles to the cutting edge 21, e. g. as indicated by the broken line 23 in Fig. 4b, would show a curved contour. Such a contour, accurately duplicated in both lips of the drill, with predetermined maximum and minimum relief angles, provides a combination of maximum relief for fast cutting and a maximum cutting edge strength and durability (minimum initial relief angle at the cutting edge). The arcuate contour of the relief angle is shown again at 23 in Fig. 4, on the drill face that is about to be ground. The grinding of the arcuate relief contour is produced by a combination of arcuate swinging of the drill about the axis of the arbor 24 and rotation of the drill about its own axis. Thus the surface that is ground on the end of a lip of the drill is in general a conical surface, modified by the relief angle.

The grinding of the arcuate relief contour is provided for by mounting the chuck 20 for rotation about its own axis in a yoke 36, carried by an arbor 24, which is mounted for rotation in the cylindrical bearing 25. The axis of the bearing 25 is indicated at 26 in Fig. 4, and is spaced outwardly from the periphery of the grinding wheel 15 a distance which determines the radius of curvature of the relief angle contour 23. The bearing 25 is carried on the end of an arm 27 which at its lower end is mounted for swinging movement on a hollow shaft 28, between limits the inner of which is determined by the engagement of a set screw 29 with a stop finger 30 and the outer of which is determined by the engagement of the arm 27 against a stop finger 31. Thus it is possible, by adjusting the set screw 29, to adjust the inner limit of swinging movement and thereby vary the radius of curvature of the relief contour 23. The stop fingers 30 and 31 are carried by a band 32 which encircles the shaft 28. The arm 27 is bifurcated at its lower end, the two fusions 34 comprising collars which encircle and bear upon the shafts 28 and which are separated by a slot 35 in which the band 32 is received.

The swinging movement of the arm 27 provides for applying the drill to the periphery of the grinding wheel at the beginning of the grinding operation and retracting the drill from the grinding wheel at the end of that operation. Between grinding operations, the chuck is indexed so as to bring the other lip of the drill into grinding position.

Rotation of the drill during a grinding operation is provided for by rotatable mounting of the chuck 20 in the yoke 36. Such rotatable mounting also provides for the indexing of the drill between the two grinding positions. The yoke 36 has a pair of arms 37 and 38 in the form of rings having bearing bores in which is rotatably mounted a cylindrical tubular quill 39. The chuck, which will be described in detail hereinafter, includes jaws 40 which are mounted within the quill 39, and an annular operating barrel 41 which encircles the quill 39 and is confined between the annular bearing arms 37 and 38 of the yoke 36. A collar 42, surrounding the projecting rear end of the quill 39 and pinned thereto at 43, is provided with a plurality of circumferentially spaced apertures 44 which determine the various positions to which the chuck may be indexed. A ring 45, rotatably mounted on the collar 42, carries a tubular lever 46 which projects radially therefrom. Within the lever 46 is a slidably mounted a shaft 47 the inner end of which has a latch pin 48 adapted to enter one of the apertures 44 under the urge of a coil spring 49 compressed between the closed outer end of the tubular lever 46 and a washer 50 that is pinned onto the latch pin 48 and is slidable within the bore of the lever 46. At its outer end the shaft 47 carries a knob 51 which may be grasped by the operator so that the shaft 47 may be pulled outwardly, unlatching the chuck 20 for rotative adjustment to index the drill to a new grinding position. During such rotative adjustment, the quill 39 rotates within the bearing bores of the yoke arms 37 and 38, the entire chuck rotating as a unit.

During the rotative movement which effects the grinding of the clearance contour 23, the ring 45 remains latched to the quill 39 and rotates with it. Such rotative movement is imparted through the lever 46, 47, and results in combined rotation of the chuck about its axis and downward swinging movement of the chuck from the minimum to the maximum clearance angle hereinbefore referred to. Such downward swinging movement is provided for by the mounting of the chuck through the medium of the yoke 36 in a fork 52

55 which is carried on one end of the arbor 24 so that the entire chuck may swing about the axis of the bearing 25, and by linking the ring 45 through a post 53 to a elbow linkage comprising arms 54 and 55 and a socket 56 such that the outer end of the post 53, which is universally pivoted in the socket 56, is supported at a fixed height (determined by the plane of horizontal swinging movement of the arms 54 and 55) so that the ring 45, when rotated, is constrained to swing bodily about the center of pivotal movement of the end of the post 53 and the socket 56. Consequently, a clockwise movement of the ring 45, as viewed from the rear end of the chuck (the operator's view point), will result simultaneously in clockwise rotation of the drill and downward swinging movement of the fork 52 and the entire chuck assembly around the axis 26 of the bearing 25 (in a counter-clockwise direction as viewed in Fig. 3). The upper and lower limits of such swinging movement are shown in full lines and dotted lines.

respectively in both Figs. 1 and 4. Fig. 1 also indicates how the downward swinging movement is brought about by moving the lever 46, 47 in a clockwise direction, indicated by the arrow 51.

The arm 54 is pivoted at 58 to the bearing 25 and at 59 to the arm 55. The arm 55 is pivoted at 60 to the socket 56. The post 53 is rigidly fixed in the ring 45, as indicated in Fig. 7.

Fig. 2a illustrates a modification of the linkage 53, 54 in which the post 53a swivels in a sleeve 53b that has an inturned end edge 53c embracing an annular bead 53d on the post 53a so as to retain the post against axial movement in the sleeve. The other end of the sleeve 53b is formed with a pair of ears 53e between which is hinged, on a pin 53f, a lug on the end of a universal coupling member 56a. The member 56a is pivoted, at 60 on an axis at right angles to the hinge pin 53f, to the arm 55.

The fork 52 embraces the arm 31 of the yoke 36 and is connected thereto by diametrically opposed pivots 61. The heel 62 of the fork 52, where it joins the arbor 24, is provided with a lug 63 which is embraced by a pair of links 64, pivoted thereto at 65. The links 64 also embrace the bridging portion 66 of the yoke 36, which bridging portion is provided with a longitudinally extending slot 67. A bolt 68 extends through each of the arms 64 and the slot 67 and has a headed thumb nut 69 threaded upon its upper end. By tightening the thumb nut 69, the links 64 may be clamped against the sides of the bridging portion 66 of the yoke 36 so as to lock the yoke 36 in a selected position of adjustment. By loosening the thumb nut 69, the entire chuck and yoke assembly may be swung about the axis of the pivot 61, relative to the fork 52, thereby to change the angle subtended between the chuck axis and the plane of the grinding wheel (and to vary the coning angle c of the drill point).

During the adjustment of the coning angle, the arms 54 and 55 may separate or move together in order to permit the chuck to be shifted horizontally, while maintaining the vertical level of the socket 56.

The heel 62 of the fork 52 is provided with a lug 70 which moves between the extremities of a notch 71 in a stop member 72 carried by the bearing 25. The stop member 72 is arched to conform to the curvature of the outer surface of the bearing 25 and is provided with a slot 73 through which a screw 74 is threaded into the bearing 25, to secure the stop member against the bearing. By loosening the screw 74 the stop member 72 may be adjusted to selected positions, within the limits provided by the slot 73. Thus the limits of downward swinging movement of the chuck can be varied. Ordinarily, such adjustment will be effected for the purpose of setting the upper limits of movement which determines the minimum clearance angle, the angle at the cutting edge being more important than the angle at the heel, insofar as fine adjustment of the angle is concerned. The heel 62 provides a shoulder 75 (Fig. 7) which bears against one end of the bearing 25. A washer 76, secured to the end of the arbor 24 by a cap screw 77, bears against the other end of the bearing 25, to securely hold the arbor against longitudinal movement.

Translatory movement of the arm 27 so as to move the chuck past the periphery of the grinding wheel, is provided for by a screw shaft 78 which is mounted for rotation in bearings 79 on the base 17 and which is threaded through a lug

80 attached to the ring 32 and projecting upwardly through a longitudinal slot 81 in the shaft 28. The lug 80 also functions as a key, operating in the slot 81, to hold the ring 32 against rotation. The shaft 18 may be provided with suitable heads 82 at its respective ends, bearing against the bearing 79 to hold the shaft against endwise movement, and with a handle 83 by means of which it may be rotated. Movement is transmitted from the shaft to the ring 32 and from the ring 32 to the arm 27. In my improved chuck mechanism, the jaws 40 are pivoted within the quill 39 by means of trunnions 84 and 85 on each jaw, pivotally received in bearings 86 in the quill 39. The trunnions 84 and 85 extend in the same direction so that a jaw may be inserted or removed from the quill by endwise movement of the jaw. The trunnions 84, 85 are located at one side of a jaw while the biting edge 87 thereof is at the opposite sides of the jaw. Consequently, the biting edges 87 may swing inwardly toward the center of the quill, to engage the periphery of a drill or other tool inserted into the chuck. The jaws are provided with fingers 88 which extend outwardly through slots 89 in the quill and cooperate with operating rings 90 which are keyed into the operating barrel 41 by means of cylindrical keys 92. The keys 92 are engaged in key slots in the peripheries of the rings 90, and in slots in the annular inner wall of the barrel 41. Spacer rings 93 are interposed between operating rings 90. The ring 93 at one end of the chuck is retained by a rolled edge on the peripheral wall of the barrel and cooperates with an integral bottom 93' of the barrel to confine the other rings 93 and 90.

Each operating ring 90 has an internal cam face 94 of helical shape and, at the outer end thereof, a reentrant finger 95. The cam surfaces 94 define cut out spaces in the rings 90, in which the respective levers 88 are received, and extend through 360 degrees.

In the operation of the chuck, rotation of the operating barrel 41 in the counterclockwise direction as viewed in Fig. 8 will cause the cam surfaces 94 to bear against the outer ends of the levers 88, moving them inwardly and causing the jaws to move into clamping engagement with a tool embraced therebetween. During such movement, the quill 39 may be held against rotation by holding the handle 46, 47 while it is latched into the collar 42. When it is desired to release the chuck, the operating sleeve is rotated in the counterclockwise direction, and the jaws will be moved outwardly by the action of small mouse trap springs 97 encircling the trunnions 84 and bearing against the inner wall of the quill and against the jaws respectively. Movement of the operating ring in the opening direction is limited by engagement of the finger 95 against the levers 88.

In a drill grinding operation, a drill is first inserted into the chuck and the chuck fastened as described above, after it has been presented to the periphery of the grinding wheel to determine its proper location lengthwise of the chuck. The chuck is then rotated, with the shaft 47 unlatched from the quill, and the handle 46 in the raised position, until one of the cutting edges of the drill is disposed substantially horizontally and in contact with the periphery of the grinding wheel. The arm 27 is then retracted and the grinding wheel is rotated. The arm 27 is then advanced, while the handle 46 is held in the

raised positions, until the cutting edge of the drill engages the grinding wheel. Still holding the arm 21 in the forward position, the operator moves the handle 46, 47 in the clockwise direction indicated by the arrow 51, simultaneously rotating the end face of the drill against the periphery of the grinding wheel about the axis of the drill and tilting the drill axis downwardly about the axis of bearing 25 from the full line position to the dotted line position shown in Fig. 4. This compound movement will produce exactly the desired relief angle on the end face of the drill while maintaining the proper coning angle. As previously stated, the downward swinging movement is derived from the clockwise rotational movement of the handle 46, 47, as the result of the post 53 pivoting at the center of the socket 56, the vertical position of which is maintained by the elbow linkage 54, 55. At the same time, the elbow linkage permits the outer end of the chuck to swing slightly inwardly toward the axis of the grinding wheel in order to follow the arcuate path of movement dictated by the fork 52 as it rotates in the bearing 25. The starting position of the chuck in this downward swinging movement is determined by the engagement of the lug 70 against the forward extremity of the notch 11. The stop member 72 may be adjusted in order to secure exactly the right starting position to provide the desired initial relief angle at the cutting edge of the drill. When it is desired to adjust the coning angle, the thumb nut 69 is loosened and the chuck is swung bodily outwardly or inwardly until the desired angle is reached, and the thumb nut 69 is again tightened. During such swinging movement of the chuck, the elbow linkage 54, 55 opens or closes in order to follow the movement of the post 53 in a horizontal plane.

I claim:

1. Drill grinding apparatus for positioning a twist drill for grinding on the periphery of a grinding wheel, comprising, in combination with a base, an arm hinged at its lower end to said base on a horizontal axis and projecting upwardly, a bearing having an axis parallel to the axis of the grinding wheel, carried at the upper end of said arm, a swinging member journaled in said bearing, a chuck carrying member hinged to said swinging member, a chuck rotatably mounted in said chuck carrying member with its axis normally disposed at an angle to the plane of said grinding wheel, whereby to determine a coning angle for the end of a twist drill, a ring rotatably mounted on said chuck, a ring operating handle secured to said ring, a post secured to said ring and projecting radially therefrom, linkage hinged to said bearing for movement constrained to a fixed plane, a universally pivotal connection between the free end of said linkage and the outer end of said post whereby said post is constrained to remain in said fixed plane and whereby by swinging said handle an operator may simultaneously rotate said chuck and constrain its outer end to tilt about the center of universal pivotal movement of the outer end of said post, thereby simultaneously rotating the drill against the periphery of the grinding wheel and tilting the drill to produce the desired clearance angle.

2. Apparatus as defined in claim 1, in which said handle includes means for latching said ring to said chuck so as to transmit rotative movement from the ring to the chuck or, in the alternative, when unlatched, to permit the chuck

to be indexed to present a different lip of the drill to the grinding wheel.

3. Apparatus as defined in claim 1, wherein said chuck holding member comprises a yoke having a longitudinally slotted bridging portion, and including a pair of links each pivoted at one end to said swinging member and at their other ends carrying a means for clamping them to said bridging portion, said clamping means extending through and being guided in said slots.

4. Apparatus as defined in claim 1, including stop means for limiting the swinging movement of said supporting arm with reference to said base, together with means for adjusting the forward limit of movement so as to adjust the presentation of a drill to said grinding wheel.

5. Apparatus as defined in claim 1, including means in which the lower end of said arm is mounted for translatory movement of the chuck across the face of the grinding wheel.

6. Drill grinding apparatus for positioning a twist drill for grinding on the periphery of a grinding wheel, comprising, in combination with a base, an arm hinged at its lower end to said base on a horizontal axis and projecting upwardly, a bearing having an axis parallel to the axis of the grinding wheel, carried at the upper end of said arm, a swinging member journaled in said bearing, a chuck carrying member hinged to said swinging member, a chuck rotatably mounted in said chuck carrying member with its axis normally disposed at an angle to the plane of said grinding wheel, whereby to determine a coning angle for the end of a twist drill, a ring rotatably mounted on said chuck, a ring operating handle secured to said ring, means connecting said ring to said bearing for translating swinging movement of said handle into combined rotating movement of the chuck about its own axis and tilting movement about its axis of movement in said chuck carrying member for simultaneously rotating the drill against the periphery of the grinding wheel and tilting the drill to produce the desired clearance angle, said handle including means to latch said ring to said chuck to transmit rotative movement from the handle to the chuck and, when unlatched, to provide for indexing the chuck to present different lips of the drill to the grinding wheel.

7. Apparatus as defined in claim 6, including stop means for limiting the swinging movement of said supporting arm with reference to said base, together with means for adjusting the forward limit of movement so as to adjust the presentation of a drill to said grinding wheel.

8. Apparatus as defined in claim 6, including means in which the lower end of said arm is mounted for translatory movement of the chuck across the face of the grinding wheel.
